N. P. J. C. CARSLUND,
ANTISLIPPING DEVICE FOR SHOES,
APPLICATION FILED NOV. 14, 1919.

1,362,225.

Patented Dec. 14, 1920.

Inventor

N. P. J. C. Carlslund.

By *Alfred J. Randolph*,
Attorney

UNITED STATES PATENT OFFICE.

NIELS P. J. C. CARSLUND, OF WEST NEW YORK, NEW JERSEY.

ANTISLIPPING DEVICE FOR SHOES.

1,362,225.

Specification of Letters Patent. Patented Dec. 14, 1920.

Application filed November 14, 1919. Serial No. 338,074.

To all whom it may concern:

Be it known that I, NIELS P. J. C. CARSLUND, a citizen of the United States, residing at West New York, in the county of Hudson and State of New Jersey, have invented certain new and useful Improvements in Antislipping Devices for Shoes; and I do hereby declare the following to be a full, clear, and exact description of the invention, such as will enable others skilled in the art to which it appertains to make and use the same.

This invention relates to shoe attachments and the primary object of the invention is to provide an improved device adapted to be attached to a shoe to prevent slipping of the shoe on a slippery surface, thereby facilitating the walking on ice and the like.

Another object of the invention is to provide an improved anti-skidding device for shoes, which can be readily and quickly placed on or removed from a pair of shoes and prevented from accidental displacement while on the shoes.

A further object of the invention is to provide an improved anti-slipping device for shoes embodying longitudinal and transverse chains adapted to provide gripping means and means for holding said chains in operative position on a shoe.

A still further object of the invention is to provide an improved anti-skidding device for shoes of the above character, which is durable and efficient in use, one that is simple and easy to manufacture, and one which can be placed upon the market at a reasonable cost.

With these and other objects in view, the invention consists in the novel construction, arrangement and formation of parts, as will be hereinafter more fully described, claimed and illustrated in the accompanying drawings forming a part thereof, in which:

Figure 1 is a side elevation of the improved device showing the same attached to a shoe,

Fig. 2 is a bottom plan view of the same, and

Fig. 3 is a detail perspective view of the heel attaching plate.

Referring to the drawings in detail, wherein similar reference characters designate corresponding parts throughout the several views, the numeral 1 generally indicates the

improved anti-skid attachment for shoes which is shown attached to a shoe of the ordinary and preferred construction including the sole 3 and the heel 4. The improved attachment 1 is formed from chain sections 60 and includes the outer chain section 5, which extends around the edge of the sole and terminates at the instep portion of the shoe.

The side chains 5 are connected by transverse chains 6 as clearly shown in Fig. 2 65 of the drawings. The chains 5 and 6 are adapted to engage the lower surface of the sole and are held against downward movement by an upper chain 7 which extends in parallel relation to the chains 5 and is 70 positioned around the upper edge of the sole, and the chains 5 and 7 are connected by depending links 8.

The attachment 1 also includes a heel section 9, which includes an arcuate attaching plate 10, which is adapted to embrace and extend around the outer surface of the heel. The inner surface of the arcuate plate 10 at the rear end thereof is provided with inwardly extending sharpened teeth 11 which 80 are adapted to bite into the heel to prevent displacement of the arcuate plate. The forward ends of the arcuate plate 10 are bent back to provide eyes 12, in which are secured the rear terminals of contractile coil 85 springs 13, which have their forward terminals secured to the ends of the chain 8.

The contractile coil springs 13 hold the arcuate plate 10 in correct position on the heel and draw the same forwardly and 90 draw the chain 8 rearwardly, and into tight engagement with the forward portion of the shoe, and prevent accidental displacement of the device. Cross chains 14 extend transversely across the heel and have their terminals connected to the lower side edges of the arcuate plate 10, and these cross chains 14 are connected together at their central portions by a relatively small chain 15.

It is a well known fact that chains provide an exceptionally durable and efficient means for preventing slipping on a wet or icy surface, and from the foregoing description, it can be seen that an improved device embodying chains as an anti-skidding 105 element is provided for shoes, which can be readily and quickly applied to shoes of all descriptions and sizes and effectively prevented from accidental displacement.

In practice, I have found that the form 110

of my invention, illustrated in the accompanying drawings and referred to in the above description, as the preferred embodiment, is the most efficient and practical; 5 yet realizing the conditions concurrent with the adoption of my device will necessarily vary, I desire to emphasize the fact that various minor changes in details of construction, proportion and arrangement of 10 parts may be resorted to, when required without sacrificing any of the advantages of my invention as set forth.

Having thus described my invention what I claim as new is:—

- 15 1. An anti-slipping device for shoes embodying a lower side chain and an upper side chain for clamping engagement with the upper side of a shoe sole, connecting chains for said lower and upper side chains, 20 a heel encircling member including bottom chains, and means for resiliently connecting the heel encircling member with the upper side chains.
2. An anti-slipping device for shoes embodying a continuous lower side chain, 25 transverse members connecting the separated portions of said continuous lower side chain, an upper side chain for clamping engagement with the upper side of a shoe sole, 30 a heel encircling member including bottom

chain members, and resilient connections between said heel encircling member and the upper side chains.

3. In combination with a shoe including a sole and a heel, of an anti-slipping device therefor including a side chain arranged to extend around the outer edge of the sole to engage the lower surface thereof, transverse chains connecting opposite portions of the side chain, an attaching chain 40 extending in parallel relation to the side chain and arranged to engage the upper edge of the sole, links connecting the attaching chain and side chain, an arcuate plate arranged to engage the outer surface of the 45 heel of the shoe, penetrating points carried by the plate, transverse chains arranged to extend across the heel and having their terminals secured to the plate, and contractile coil springs having their terminals connected to the terminals of the heel plate and the attaching chain, as and for the purpose specified.

In testimony whereof I affix my signature in presence of two witnesses.

NIELS P. J. C. CARSLUND.
